CLAIM

The ornamental design for a well casing cap, as shown and described.

DESCRIPTION

FIG. 1 is a top plan view of a well casing cap embodying my invention.

FIG. 2 is a bottom plan view of the well casing cap shown in FIG. 1 and embodying my invention; and,

FIG. 3 is a side elevation of the right side of the well casing cap shown in FIG. 1 and embodying my invention; the left side is a mirror image of the right.

1 Claim, 1 Drawing Sheet

FIG. 3
